RECLINING SEAT MECHANISM

Ernie J. Beck, Chicago, Ill., assignor to S. Karpen & Bros., Chicago, Ill., a corporation of Illinois

Application August 28, 1939, Serial No. 292,359

4 Claims. (Cl. 155—161)

This invention relates to reclining seat mechanism. It is particularly useful in connection with seats for buses, railway cars, airplanes, etc.

An object of the invention is to provide reclining seat mechanism of extremely simple and inexpensive construction which may be employed for maintaining a reclining seat in the desired angular position. A further object is to provide sturdy and compact mechanism housed within the arm of the seat which can be readily adjusted for maintaining a reclining seat in the desired angular adjusted position. Other specific objects and advantages will appear as the specification proceeds.

The invention is illustrated, in a preferred embodiment, by the accompanying drawings, in which—

Figure 1 is a broken side view in elevation of a seat equipped with mechanism embodying my invention; Fig. 2, a side view in elevation of the back adjusting and supporting mechanism, a portion of the mechanism being shown in longitudinal section; Fig. 3, a transverse sectional view, the section being taken as indicated at line 3 of Fig. 2; Fig. 4, a transverse sectional view, the section being taken as indicated at line 4 of Fig. 2; Fig. 5, a transverse sectional view, the section being taken as indicated at line 5 of Fig. 2; and Fig. 6, a broken sectional view, the section being taken as indicated at line 6 of Fig. 2.

In the illustration given, A designates a seat suitable for a railway, bus, airplane, and the like. Since the seat is of well known construction and does not in itself embody the invention, a detailed description thereof is believed unnecessary.

The seat A is provided with a frame 10 supported by legs 11. The frame provides a hollow metal side member 12 in which the reclining back supporting mechanism B, embodying the invention herein, is disclosed. The reclining back C is secured at its lower end and on each side to the metal arms 13 by means of bolts, screws, etc. passing through the openings 14 in the web central portion of the arm. The upper portion of the arm 13 is provided with a bearing sleeve 15 which receives a shaft 16 carried by the frame. The lower end of the arm 13 is pivotally received in the bifurcated end of the connecting member 16. The forward end of the member 16 is threaded to receive the connecting rod 17. The forward end of rod 17 is threaded into an enlarged plunger rod 18.

The plunger rod 18 is received for sliding movement within a tubular channel 19 provided

by the pivoted member 20. The pivoted member 20, as shown in Figure 3, is generally of an I-beam construction except that it provides centrally a tubular body 21 providing the inner tubular channel 19. The web portions 22, which join the horizontal flanges 23 to the cylindrical body 21. The forward end of the member 20 is pivoted at 24 to a standard 25 riveted or welded to the frame 12.

10 A spring 26 is housed within the channel 19 and normally urges the plunger rod 18 in a rearward direction. The portion of the tubular body 21 adjacent to the spring 26 is shown provided with longitudinal apertures 27. The plunger 18 is provided on its top portion with a series of spaced locking recesses or indentations 28. The plunger 18 also carries on its side a stop head 29 secured by a threaded bolt 30 to the member 18. The head 29 moves within a slotted channel 31 in the tubular body 21. The length of the channel 31 limits the movement of the plunger 18.

15 The means for locking the plunger 18 in any desired position will now be described. At the 25 point indicated by the numeral 32 and as shown in Fig. 4, the member 20 is provided with a U-shaped recess 33. Mounted for vertical movement within the recess 33 is the toothed projection or slide 34. The member 34 is provided with 30 a pair of teeth 35 adapted to engage two of the recesses 28. The member 34 is connected by a link member 36 to an actuating finger 37 by means of pin 38. It will be noted that the link 36 is pivotally connected at its lower end to member 34 by pin 39.

35 Any suitable means for actuating the finger 37 may be employed. In the illustration given, the finger 37 is formed as an integral part of a lever arm 40. At an intermediate point the lever arm 40 is provided with depending spaced apart ears 41 which receive a lug 42 provided as an integral extension of the member 20. The ears 41 are pivotally mounted on the lug 42 by the pin 43.

40 In order to maintain the seat adjusting mechanism entirely within the side frame 12, I prefer to extend the lever arm 40 to a point below a reciprocally mounted plunger 44. The plunger 44 extends through and is guided by a sleeve 45 carried by the frame A. The plunger 44 is provided 45 at its bottom side with a slot 46 receiving the forward end of the lever 40. A pin 47 passes through an elongated slot 48 in the lever 40 and has its ends received within the divided ends of the plunger 44.

50 The web portions 22 extending on either side

of the cylindrical body 21 brace the cylindrical body casting. At the same time, the upper web provides a pivot support 42 for the lever 40.

Operation

In the operation of the reclining back, it will be noted that the pivoted back is normally urged toward upright position by the spring 26. Spring 26 presses plunger 18, connecting rod 17, connecting member 16 and the member 13 in a rearward direction. This causes the back C, which swings about the pivot 16, to move forwardly toward upright position. When the occupant desires to move the seat back rearwardly, he presses down upon the plunger 44 so as to actuate lever 40, the pin 47 traveling within the slot 48 of the lever arm 40. By this movement, the actuating finger 37 is raised and this causes the locking member 34 to be lifted, the teeth 35 leaving the recesses 28.

The plunger 18 is now free to slide within the channel 19 and, as the occupant leans rearwardly against the seat back C, the plunger 18 is forced forwardly against spring 26 until the desired inclination of the seat back is reached. The plunger 44 is then released, and the member 34 drops, under the force of the springs 49, into locking position with the teeth 35 engaging the recesses 28 brought into alignment therewith. The engagement of teeth 35 with the recesses 28 now maintains the plunger in the new position, and the reclining seat C will stay in that position until the plunger 44 is again manipulated.

The structure is simple, compact and completely housed within the side frame 12, the only exposed mechanism being the plunger 44.

While in the foregoing description I have set forth certain details illustrating the operation of the invention, it will be understood that such details may be modified and changed widely without departing from the spirit of my invention. I wish it to be understood that I do not desire to be limited to the exact details of construction shown and described, for obvious modifications will occur to a person skilled in the art.

I claim:

1. In combination with a seat frame and a seat back pivotally mounted thereon, a plunger arm pivotally mounted on said seat back and provided at its forward end with spaced locking indentations, an integral casting providing a central tubular member and vertical web portions on either side thereof, a portion of the upper web and the top portion of said tubular member being broken away to expose said locking indentations, means carried by the seat frame for pivotally supporting the front end of the tubular member, a locking member equipped with a pair of teeth slidably mounted in the broken away

portion of said web, said teeth being adapted to engage a pair of said locking indentations, a lever pivotally mounted upon the top web of said casting and having a rearwardly extending portion pivotally secured to said locking member, and means supported in the frame for actuating said lever.

2. In combination with a seat frame and a seat back pivotally mounted thereon, a plunger arm pivotally mounted on said seat back and provided with spaced locking indentations, an integral casting providing a central tubular member and vertical web portions on either side thereof extending longitudinally of the tubular member, a portion of the upper web and the top portion of the tubular member being broken away to expose said locking indentations, means carried by the seat frame for pivotally supporting the front end of said tubular member, a locking member mounted in the broken away portion of the web, and means for releasably bringing said locking member into engagement with the locking indentations.

3. In combination with a seat frame and a seat back pivotally mounted on said frame, a plunger arm pivotally connected to the seat back, a tubular member receiving the forward end of said arm and provided with a vertical web extending longitudinally of the member, a spring housed within the tubular member normally urging the arm toward rearward position, means for pivotally supporting the front end of said tubular member on the front portion of said frame, said plunger arm having locking indentations therein, a lug carried by said web, a lever pivotally mounted upon said lug, a locking member slidably in said tubular member carried by the rear end portion of said lever, and means for actuating said lever to bring said locking member releasably into engagement with said locking indentations.

4. In combination with a seat frame and seat back pivotally mounted thereon, a plunger arm pivotally mounted on said seat back and provided at its forward end with spaced locking indentations, a tubular member receiving said plunger arm and pivotally carried by said frame, a vertical integral web on said tubular member extending longitudinally along the same, said member and said web being substantially coextensive in length, a lever mounted upon said web, a locking member carried by said web on said tubular member and pivotally secured to said lever, said member being equipped with a plurality of teeth for engaging said locking indentations, and means extending through said seat frame and engaging said lever for operating the same to withdraw said teeth from said indentations.
